UNITED STATES PATENT OFFICE

JOSEPH D. BROWN, OF NEW YORK, N. Y., ASSIGNOR TO HATFIELD WIRE AND CABLE CO.,
OF HILLSIDE, NEW JERSEY

DESIGN FOR AN ELECTRICAL CONNECTION PLUG

Application filed June 15, 1932. Serial No. 44,080. Term of patent 7 years.

To all whom it may concern:

Be it known that I, JOSEPH D. BROWN, a citizen of the United States, residing at New York, in the county of New York, State of New York, have invented a new, original, and ornamental Design for an Electric Connection Plug, of which the following is a description, reference being had to the accompanying drawing, forming a part thereof.

In the drawing Figure 1 shows an elevational view of the plug, while Figure 2 shows an end view of the terminal end of the plug.

I claim:

The ornamental design for an electrical connection plug as shown.

In testimony whereof, I affix my signature.

JOSEPH D. BROWN.
